UNITED STATES PATENT OFFICE.

CHARLES C. WORTHINGTON, OF DUNFIELD, NEW JERSEY.

GOLF BAG.

Application filed July 21, 1922. Serial No. 576,419.

To all whom it may concern:

Be it known that I, CHARLES C. WORTHINGTON, a citizen of the United States, residing in Dunfield, Warren County, in the State of New Jersey, and whose post-office address is Shawnee-on-Delaware, Pennsylvania, have invented the following-described Improvements in Golf Bags.

My invention relates to golf bags and is 10 designed to secure the advantages of durability, reduced size, light weight, cleanliness, convenience in transportation and of protecting the golf clubs from the injurious effect of rubbing and knocking contact with 15 each other.

The golf bag herein described is made up of a number of tubes of light material, each of which is preferably adapted to hold but a single club and all of which may be secured together flexibly and separably so that they may assume for convenience in travelling either a flat formation or be folded, or rolled up when carried by hand. The number of these tubes may be readily increased 20 or diminished so that the total number need not at any time be greater than the desired number of clubs. In transporting this bag, if the tubes are spread out flat they can be conveniently packed in a trunk or they can 25 be folded or rolled up in the circular form usual in the ordinary golf bag of commerce.

The bag contains practically no waste space. The diameter of none of the tubes need be greater than is required to properly accommodate the club. If each club is in a tube by itself it will not be subjected to the rubbing and knocking of one club against another, that always takes place where more than one club is carried in one 30 compartment. This rubbing and knocking chips, dents and wears the grips of the clubs and their shafts.

The tubes are inexpensive. They are preferably made of aluminum or some other light, stiff and durable material. They can be readily cleaned and kept sanitary and are of attractive and neat appearance.

Reference is made to the two sheets of drawings wherein—

50 Fig. 1 is a perspective view of the bag with the tubes which compose it shown in one plane being held in proper relative position by a strap forming one kind of flexible fastening;

Fig. 2 is a detail perspective showing a form of strap fastening for the handle;

Fig. 3 is a vertical section through the bag showing one of the forms of flexible fasteners and its position on the tubes;

Fig. 4 is a detail elevation partly in section of one of the tubes broken away in the middle;

Fig. 5 is a vertical section as in Fig. 3 but showing a riveted hinged connection;

Fig. 6 is an elevation of tubes connected 65 as in Fig. 5, the tubes being broken away in the middle and only two lugs being shown on each tube;

Fig. 7 is a section of the tubes connected as in Fig. 5 folded or rolled into circular 70 form;

Fig. 8 is a detail elevation partly in section showing another form of flexible fastener consisting of a sliding ring permitting, except as to endwise movement, the same 75 relative motion of the tubes when connected by it as the connection of Fig. 1;

Fig. 9 is a perspective view of one of the rings in Fig. 8;

Fig. 10 is a section of a bag, whose tubes 80 are connected as in Fig. 8, rolled into circular form and enclosing a larger tube, and

Fig. 11 is a perspective view corresponding to Fig. 10 but on a smaller scale.

The individual duplicate tubes 1 are flexibly and separably secured together in any desired number by any suitable means as in Figs. 1, 5 and 8. In Fig. 1 they are illustrated as held by the two straps 2 which interlace the tubes, passing alternately on 90 opposite sides of successive tubes through the keepers 3 with which each tube is provided, and returning in the same way in reverse direction. By unbuckling the straps, tubes may be removed or added as circumstances require. Each tube is shown with the edge of its open end rounded or beaded as indicated at 4, as reinforcement. The opposite ends of the tubes are preferably closed in any suitable manner so as to support the ends of the club shafts and prevent the club heads from resting on the upper ends of the tubes. The bottom of the tube is provided with an opening 5 for drainage of such dirt or water as may enter. A handle 6 is shown secured to a tube by a strap 7, passing around the same and taking through a keeper 8 in one end of the handle 6, and by a special handle strap 9 taking through the keeper 10, as illustrated in Fig. 105

2. Another method of fastening the handle is illustrated in Fig. 1. A shoulder strap 110

is also shown connected to the uppermost tube by its buckles 12, being most conveniently buckled at one end to the strap 2 adjacent the closed ends of the tubes and at 5 the other through a slot 13 in the upturned forward end of the handle 6. It will be apparent that the tubes being flexibly connected will either hang in the same plane—one above the other—when the handle 6 or 10 the shoulder strap 11 is used for their support, or when rolled into the relation shown in Figs. 7, 10 and 11 may be carried by the same handle 6 or shoulder strap 11.

The tubes when strung together as in Fig. 15 1 will hang in the same plane one directly above the other as shown in the said figure, the strap-lacing connection being not only flexible but loose enough to permit the skewing necessary to enable the tubes to assume 20 a position in the same plane with their open ends in line vertically.

In the arrangement of tube fastening illustrated in Figs. 5, 6 and 7, each tube is provided with two fasteners 14 at each end 25 either riveted or soldered to the tube in the same circumferential plane and 180° apart. These may be placed in the same location with reference to the extreme ends of the tube as the keepers 3 in Fig. 1. The tubes 30 may be joined flexibly together by means of these fasteners by inserting loose pins 15 in the holes 16 of the fasteners 14 and holding the said pins in place with a split pin or other obvious means. With this form of 35 fastener the tubes may be arranged in flat or circular formation at will as shown in Figs. 5 and 7.

Another form of fastener is shown in Figs. 8, 9, 10 and 11. The fastener is made in 40 the form of a collar 17 encircling the tube and having a projection or lug 18 pierced by a hole 19. Two of these collars 17 are placed in juxtaposition at or near each end of each tube as in the case of the fasteners 14 in 45 Fig. 5 and are held in position by external circular ribs 20 spun on the tube or formed in any other suitable manner. The collars 17 fit loosely on the tube so as to enable the projecting lugs 18 when jointed by a pin 21 50 through the hole 19 with a corresponding lug on the collar of an adjoining tube, to move to any position on the circumference of the tube that may be required in arranging the bag in flat or circular shape. It will 55 be observed that the collars are shown as identical, those of each pair being reversed with respect to each other.

It is obvious that a separate tube large 60 enough to hold golf balls or other larger articles may be joined to the club tubes either as one of the series or separately. In Figs. 10 and 11 such a storage tube 22 having if desired a removable cap 23, which 65 may be held on by a bayonet joint, is shown encircled by the club tubes and forming a

component part of the bag, being removably secured thereto by any suitable means as a pair of straps 24, one at each end of the bag, passing through keepers 25 and around club tubes 1 and respectively below and above the 70 upper and the lower set of collar lugs 18 (or fasteners 14 where these are used).

While it is obviously not necessary that the component club tubes, their lugs, collars or other connecting means should be identical, it is desirable since it facilitates interchangeability and gives the bag a neat appearance.

Claims:

1. A golf bag of variable capacity made up of separate tubes each tube being adapted to hold but a single club and means for connecting said tubes flexibly and separably, said tubes forming a series the members of which may be in the same plane or which 85 may be rolled up in circular or other formation and means secured to the series for carrying the bag.

2. A golf bag made up of separately made tubes of rigid material so as to be self-supporting and maintain a substantially cylindrical shape, each tube being adapted to hold but a single club, and means for connecting said tubes flexibly, said tubes forming a series the members of which may be 95 in the same plane or which may be rolled up in circular or other formation and means secured to the series for carrying the bag.

3. As an article of manufacture, a golf bag comprising a set of separately made tubes with open upper ends and closed bottoms, each tube being formed of rigid material so as to be self-supporting and maintain a substantially cylindrical shape, and two separate means near the opposite ends of said tubes disconnected from each other save by the tubes and uniting them in parallel grouped relation.

4. A golf bag consisting of a set of separately made tubes of rigid material whereby 110 they are adapted to be self-supporting, detachably assembled, each tube forming a receptacle for a golf club and means secured to the bag for carrying it.

5. A golf bag comprising a series of separately made tubes of rigid material whereby 115 they are adapted to be self-supporting, and of a length and size adapting them to contain golf clubs, each tube having a set of spaced fasteners adjacent opposite ends of 120 the tube for holding the tubes together in substantially parallel relation.

6. A golf bag consisting of a plurality of separately made, detachably connected tubes of rigid material whereby they are adapted 125 to be self-supporting, each tube forming a receptacle for a single golf club, and means for connecting said tubes in a closed structure of a size variable by changing the number of the tubes.

7. As a new article of manufacture, a golf bag comprising a set of separately made tubes, each tube being formed of rigid material so as to maintain a substantially cylindrical shape and each tube having an open end and being adapted to hold but a single club, and means for uniting said tubes in group relation.
8. As a new article of manufacture, a golf bag consisting of a set of separately made metal tubes united adjacent their opposite ends by spaced uniting means.
9. As a new article of manufacture, a golf bag consisting of a set of separately made metal tubes having a rounded edge at their open ends and having a closed bottom united adjacent their tops and bottoms by spaced united means.
10. As a new article of manufacture, a golf bag consisting of a set of separately made metal tubes having a rounded edge at their open ends and having a closed bottom, and flexible means uniting them.
11. A golf bag comprising a series of metal tubes each having its bottom closed and its other end open and having a protecting edge at its open end and a drainage hole at its closed end and fasteners adjacent each end.
12. A golf bag consisting of a number of tubes having collars capable of turning thereon and constituting means for connecting the tubes flexibly and separably.
13. A golf bag consisting of a plurality of stiff tubes, each provided with a plurality of loose collars having means for retaining them against longitudinal displacement, and means for separably connecting said collars to adjacent tubes, whereby the shape of the golf bag may be altered and its capacity changed by varying the number of tubes.
14. A golf bag consisting of a plurality of parallel club-holding tubes flexibly connected, a relatively larger tube suitable for other articles and means for securing it to the club-holding tubes within the enclosing structure formed thereby.

In testimony whereof, I have signed this specification.

CHARLES C. WORTHINGTON.
